UNITED STATES PATENT OFFICE.

WILLIAM N. PILKINGTON, OF ST. HELENS, ENGLAND, ASSIGNOR TO PILKINGTON BROTHERS LIMITED, OF ST. HELENS, ENGLAND.

DESIGN FOR SHEET GLASS.

Application filed January 6, 1923. Serial No. 4,822. Term of patent 14 years.

To all whom it may concern:

Be it known that I, WILLIAM NORMAN PILKINGTON, subject of the King of Great Britain, residing at St. Helens, in the county of Lancaster, England, have invented a new, original, and ornamental Design for Sheet Glass, of which the following is a specification, reference being had to the accompanying drawing, forming a part thereof.

The design consists of a fanciful combination of conventional flowers, leaves and branches so arranged as to make a graceful configuration on glass to which this design is to be applied.

I claim:—

The ornamental design for sheet glass as shown.

W. N. PILKINGTON.
